MANIFOLDING

Carl W. Brenn, Montclair, N. J., assignor to Auto-graphic Register Company, Hoboken, N. J.

Application February 25, 1936, Serial No. 65,556
Renewed June 6, 1938

21 Claims. (CL 282—3)

This invention relates to manifolding.

The general aim of the invention is to provide improvements in that type of manifolding assembly, such, for instance, as is shown in U. S. patent to me No. 1,999,535, issued April 30, 1935, wherein a comparatively inexpensive box or casing made of cardboard, chip board, or other paper material is employed for containing permanently sealed within the same a pile of zigzag folded continuous writing strips. In this type of register, which is to be discarded or destroyed as soon as its contained writing strips have all been used up, the box comprises telescoping upper and lower sections secured together to prevent the box being opened without substantial destruction thereof. Such box or casing has a writing opening in its top and carries a platen or writing bed in the form of a shaped plate of metal or other relatively hard material below such opening; the manufacture of the casing being conducted and completed in such a way that when the box parts have been permanently joined as by cementing together the vertical walls of the two telescoping sections, the work sheets of the leading set extend over such plate and are exposed through such opening. The result is that when this once-use casing is delivered to the purchaser, the work sheets last mentioned are ready for use and the leading edges thereof can be readily grasped and advanced to bring a follower set of work sheets into writing position and, at the same time, to advance the work sheets of said leading set to severing position.

One of the objects of the present invention is to provide an improved metal writing plate having, among other advantages, novel cooperant relations with other parts of the casing.

Another object is to provide a writing plate as aforesaid, which also serves to provide means for properly placing in the casing the required number of carbon or transfer sheets and for holding these sheets in such manner that the width of the casing need not be increased anywhere along its length beyond that of the width of the pile of writing strips.

Still another object of the invention, aimed at the provision of a casing which will be less expensive but more rigid and rugged than heretofore, is to provide a novel type of lower section for the casing such that the same requires a relatively small total weight of material, yet with this material so distributed that surprising strength and stiffness results in the finished lower section and particularly in the complete casing when the other parts thereof are added, even when, as is

now preferred, the upper section has all its walls merely single-ply sheets of fairly light weight chip board. In attaining this object in a way now preferred, the walls of the lower section are formed of corrugated paper board; these walls are all parts of a single folded blank wherein the corrugations run in the same direction; and yet each of the two side walls, both of which are of two-ply thickness, is so established from said blank that the corrugations of one of its plies run at right angles to the corrugations of the other of its plies.

Other features and advantages will hereinafter appear.

In the accompanying drawings which show the form of this invention at present preferred—

Figure 1 is a top plan view of an assembly as manufactured and shipped to the consumer for use, but with various parts variously broken away to illustrate details of construction.

Fig. 2 is a longitudinal vertical section.

Fig. 3 is a transverse vertical section taken on the line 3—3 of Fig. 2.

Fig. 4 is a perspective view of the lower section of the casing with the writing plate applied thereto.

Fig. 5 is a perspective view showing the writing plate.

Fig. 6 is a plan view of the blank and corrugated board which is folded up to establish all the walls of the lower section, but with the corrugations not shown.

Fig. 7 is a fragmentary sectional view taken on the line 7—7 of Fig. 1 showing a detail of construction.

Fig. 8 is an enlarged detail view, showing constructionally certain elements omitted from Fig. 2 to simplify the latter where lines are necessarily placed very close together.

The device of the present invention, in the exemplifying embodiment thereof illustrated in the drawings, included a container or box having upper and lower telescoping sections 10 and 11, the former being folded up from a single blank of chip board and the latter folded up from a single blank of corrugated board. This container, when the invention is carried out in the preferred way, has a width which depends upon the width of the forms, tickets, or other work sheets which are to be packed therein, the inner width of the lower section corresponding very closely to that of the width of such work sheets. Thus, the pile of zigzag folded continuous work or writing strips when the device is finally manufactured will be disposed in the box as indicated at 12 in Figs. 2

and 3, except that ordinarily the height of the pile will be considerably greater than that shown in these views to fill completely the storage capacity of the box.

Referring to the lower section 11, the same is folded up from a single blank of corrugated board. In Fig. 6, this blank is shown, so far as the outline thereof, cuts 13 therein, and scorings 13a thereon, are concerned. The direction in which the corrugations extend over the blank, when the walls of the lower section have their corrugations run as shown in Figs. 1 to 4, is that indicated by the double line 11b in Fig. 6. This blank is preferably so designed that when the portions 14 are folded up to form the end walls 15 of the lower section, and the portions 15 are folded up to form one ply of the side walls of the lower section, thereby to establish the bottom wall 16 of the lower section, and the four sections 17 at the four corners of the blank are folded up inside the side wall plies just mentioned and placed parallel therewith, to give each of said side walls a two-ply structure, edges of the two sections 17 at one side of the blank will meet at the dot-and-dash line 15a in Fig. 6 and edges of the two sections 17 at the other side of the blank will meet at the dot-and-dash line 15b in Fig. 6. Then the corrugations of the inner plies of the side walls of the lower section 11 will run horizontally, while the corrugations of the outer plies of these walls, that is, of the plies furnished by the sections 17, will run vertically.

When these two plies of each side wall are secured together all over by a suitable adhesive, as is preferred, exceedingly strong and stiff yet light-weight side walls are provided. In the lower section thus formed, the corrugations of the bottom wall 16 run longitudinally thereof as shown in Fig. 3, and the corrugations of the end walls 14 run vertically as shown in Fig. 4.

Referring to the upper section 10, the paper-material walls thereof are desirably formed from a cruciform blank (not shown) of ordinary chip board to provide a top wall 18, end walls 19, and side walls 20, all of single ply thickness.

As will be seen from a comparison of Figs. 1 and 3, box corner metal fasteners strips 21 are applied along the corner edges between the top and side walls of the upper section, these to act as longitudinal bracing ribs for that section; and similar metal strips, as shown also at 21 in Figs. 1 and 3, are applied along the four vertical corner edges of said upper section, these latter strips acting not only to establish the upper section as such by binding together the meeting edges of its side and walls, but, also, to incorporate vertical bracing ribs for the section. These fasteners carry a plurality of integral prongs (not shown) struck out from their metal incident to the formation of their lightener holes 21a, and these prongs are sent through the paper material of the walls of the section and clenched tight against the inner sides thereof.

Reverting now to the lower section 11, in which connection see Fig. 4, similar metal fastener strips 21' are applied to the four vertical corner edges of that section and similarly secured to the paper material of the walls thereof. Thus, the lower section 11, like the upper section 10, is provided with vertical bracing ribs along its four vertical corner edges.

The structural description of this lower section 11 is completed when it is pointed out that the end wall 14 appearing to the left in Fig. 4 has

a small half-round opening cut away at about the center of its upper edge, and the inner plies 17 of the side walls of the lower section which are most remote from said half-round opening have portions cut away to provide very small rectangular recesses at the inner sides of these side walls. In Figs. 1 and 4, such half-round cutout is marked 22, and such rectangular cutouts are marked 23. These last will hereinafter be called the carbon holder pockets.

Such cutouts, which have to do with the facilities provided for the feeding of work sheets to writing position as hereinafter explained, are so located and are so relatively small that, as will be understood, their presence has no appreciable weakening effect on the lower section 11.

The upper section 10 has its top wall 18 cut away to provide a fairly long writing opening 24, which opening 24 is continued as a shorter and wider feeder opening 25. The opening 25 extends all the way to the top edge of the adjacent end wall 19 of the upper section 10, the central upper portion of which end wall has a cutout 26. This cutout 26 matches the half-round cutout 22 in the lower section 11 when the two sections are fully telescoped to complete the box.

It will be noted, referring to Fig. 1, that the right-hand limit of the writing opening 24 in the top wall 18 of the upper section is such that this opening is wholly to the left of the carbon holder pockets 23. It will be seen, also, that the writing opening 24 is of sufficiently less width than said top wall 18 to provide that fairly wide strips of such top wall, marked 18a, and stiffened by the metal corner fasteners 21 running therealong, extend not only lengthwise of the writing opening but also lengthwise of the feeder opening 25, to merge with the side portions of the adjacent end wall 19 of the top section and thus provide top corner edges at opposite sides of said end wall.

Supported on the lower section 11, so as to extend under the writing opening 24 and the feeder opening 25 in the top section 10, is a writing plate 27 of metal or other relatively hard material. This plate is desirably made of light gage metal only about as heavy as that ordinarily used for the making of so-called tin cans.

As illustrated most clearly in Fig. 5, the writing plate comprises a main portion or writing plate proper 27a having a downwardly inclined ramp 27b over which the work sheets pass toward writing position, this ramp terminating at its lower work sheet-receiving end in an undercurled edge portion 27c. Along each of its sides the writing plate has dependent flanges 27d and 27e, these flanges being staggered as shown best in Fig. 5, but so disposed that when the flanges 27d are close against the outer surfaces of the side walls of the lower section, the flanges 27a are snugly engaged with the inner surfaces of said side walls. Similarly staggered flanges 27g and 27h depend from the front end of the writing plate, these for seizing between them the inner and outer surfaces of the end wall of the lower section which has therein the half-round opening 22. Partially in the writing plate proper 27a and partially in the flange 27g is a substantially circular opening 27f, the lower portion of which matches with said opening 22, as shown in Fig. 4, when the parts are arranged as there illustrated.

Registration of the forms on the writing plate may be accomplished in any suitable or desirable way. As here shown, each form is provided with

5 a pair of form-registering apertures, and, for co-action with these apertures, the delivery end of the writing plate 27 is provided with a pair of stopping and aligning pins 28. These pins, and also that part of the opening 27j of the writing plate which is in its flange 21g and which matches the half-round opening 22 in the lower section 11, are exposed, when the box is completed by telescoping its two sections, through the feeder or delivery opening 25 in the top wall of the top section; this half-round opening 22 then matching as aforesaid the similar opening 26 in the upper section 10.

10 Referring to the carbon sheet equipment, the carbon sheet employed is a true or pre-cut sheet 29. Fig. 1 shows two of these sheets in use. These sheets trail toward the delivery end of the writing plate away from their ends which are anchored to the plate near the receiving end of the latter. As shown in Figs. 1 and 8, each anchored end of a carbon sheet 29 is held between two leaves of a longitudinally folded thin metal strip 30, said end being tightly gripped between these leaves by indentations made in the upper 15 leaf as seen in Fig. 1. The lower leaf of each of these holder strips is prolonged beyond the ends of the upper leaf, and each of these prolongations has a thin elongated slot 30a therein. These slots take small extensions 27k upstanding from the ramp 27b of the writing plate. These extensions have oppositely located ears 27m at elevated points thereon. In assembling the device, when the carbon sheet holders have been mounted to string their slots about the lower portions of these extension 27k, the ears of each such extension are oppositely twisted as indicated in Fig. 1, thus permanently to secure the carbon sheets in place. The prolongations of the carbon holders 30 which carry the slots 30a, are at their extreme 20 ends beyond such slots accommodated in the carbon holder pockets 23 in the side walls of the lower section.

25 It will be noted that the fitments just described are located beyond the side edges of the work sheets so that, as one set of work sheets is drawn forward after another over the writing plate, following the initial proper interleaving of the work sheets of the leading set with the carbon sheets in assembling the device, there is no interference 30 between these work sheets and the carbon sheets, and the carbon sheets are always in working position relative to their appointed work sheets. These carbon sheets are of such lengths forward of their points of anchorage that they extend over 35 all the parts of the work sheets on which entries will be made; the writing capacity of the carbon sheets being sufficient to take care of all the carbon copies which can be made on the total number of work sheets to be stored in the casing when 40 finished at the factory of the maker.

45 Somewhat ahead of the pins 28, the device is provided with a transverse member 31 to hold the leading ends 32a of the leading set 32 of work sheets down toward the writing plate and so 50 that the apertures in the sheets of such set cannot become accidentally detached from said pins. Here, however, this member 31 is mounted on the top wall of the upper section 10. Said member is merely a transversely rounded metal strip having 55 reduced ends or terminal tabs 31a sent through holes 21a of the corner fasteners 21 running along the sides of the top wall 18 of the upper section and through holes in said wall matching these 60 holes 21a. These holes 21a are desirably so located 65 that they are in a line crossing the device

70 perpendicular to the line of travel of the work sheets over the writing plate. Said tabs 31a, after being sent through the holes 21a, are bent toward each other and then squeezed tight against the under surface of said top wall (see Fig. 7). By a 75 construction of this kind, not only is the writing plate simplified and cheapened, but the least strong part of the upper section is strengthened and braced where such strengthening and bracing is most needed; the member 31 acting as an important bracing and stiffening member.

80 In assembling the device, the pile of zigzag folded work sheets, desirably printed and provided with transverse lines of perforations 33 between forms, is placed in the lower section 11 and the 85 leading length of the pile is looped as indicated at 34 in Fig. 2. Then, with the forms of the leading set properly interleaved with the carbon sheets 29 and with all these sheets lying on the writing plate 27, and with the carbon sheet holders 30 secured permanently in place as above explained, the writing plate is mounted on the side walls of said lower section 11 and on the end wall thereof which has the half-round opening 22. The dependent flanges of the writing plate for 90 25 embracing these walls immovably and solidly set the writing plate in the intended position; an accompanying result being that this plate acts as a tieplate, rigid in its own main or horizontal plane, to hold the major lengths of the two side 95 walls of the lower section rigid and parallel and to hold the intervening end wall of said section 30 rigidly perpendicular to such two side walls, thereby causing these three casing walls to brace and stiffen each other and in turn to brace and 35 stiffen all the five walls of the lower section.

100 The form-registering apertures of the work sheets on the writing plate having been engaged with the stopping and aligning pins 28, the upper section 10 is telescoped over the lower section 11. 40 This results in bringing the member 31 down to rest against the leading work sheets just ahead of the pins 28, so that such member applies proper downward pressure to these sheets to hold them against accidental displacement from the pins. 45 This is insured, and also sufficient space is provided between the top surface of the writing plate and the under surface of the top wall of the upper section to allow for unimpeded and easy forward feeding of the work sheets, by the provision 50 of suitable spacing means here shown as two narrow and fairly thick cardboard or wood strips 35 cemented or otherwise suitably fastened in place along the under surface of the top wall of the upper section close up against the side walls 55 of that section. As indicated in Fig. 2, these strips 35 extend from the delivery end of the casing back to the carbon holder pockets 23. Finally, the upper and lower sections of the casing 60 are secured together by a suitable adhesive—water glass for instance—the intention being that these parts 10 and 11 shall be held together against separation without destruction.

65 The operations described above are intended to be performed at the factory.

70 In use, the operator makes the desired entries upon the uppermost of the set of forms in place on the writing plate, grasps the end of these sheets by way of the thumb-opening afforded by the cutout 27j at the delivery end of the writing 75 plate, advances them one form-length by manual pull, and severs the same by holding the strips now on the writing plate and snapping the advanced sheets therefrom along a line of perforations 33. These operations are continued 80

from time to time as required until all the forms are used up and the casing ready to be destroyed or discarded, whereupon a new container with a similar preloaded supply of work sheets and carbon sheets is put into use.

5 The term "chip board" as used herein should be understood to include pressboard or cardboard of various kinds, as well as other equivalents thereof, and the term "paper material" as used herein should be understood to include chip board or corrugated board or equivalents.

10 Variations and modifications may be made within the scope of this invention and portions of the improvements may be used without others.

15 I claim:

1. In a manifolding assemblage having a one-use casing to be discarded when the work sheet contents are used up, including a pair of telescoping upper and lower sections to be joined 20 against separation without destruction, both of said sections having all their walls of paper material, the top wall of the upper section having a writing opening, the combination with said sections of a metal writing plate interposed between them, 25 said plate having depending flanges some for engaging the inner surfaces of the side walls and of the intervening end wall of the lower section and some for engaging the outer surfaces of said three walls.

30 2. In a manifolding assemblage having a one-use casing to be discarded when the work sheet contents are used up, including a pair of telescoping upper and lower sections to be joined against separation without destruction, the top 35 wall of the upper section having a writing opening, the combination with said sections of a metal writing plate interposed between them, said plate having depending flanges some for engaging the inner surfaces of the side walls and of the intervening end wall of the lower section and some for engaging the outer surfaces of said three walls, the walls of said sections being made of paper material with the side walls being reinforced throughout their length and bracing ribs carried by said sections, said ribs applied along vertical corner edges on both sections and along side corner edges of the top wall of the upper section.

40 3. In a manifolding assemblage having a one-use casing to be discarded when the work sheet contents are used up, including a pair of telescoping upper and lower sections to be joined against separation without destruction, both of said sections having all their walls of paper material, the combination with said sections of a metal writing plate interposed between them, 45 of the intervening end wall of the lower section and some for engaging the outer surfaces of said three walls, the walls of said sections being made of paper material; and bracing ribs secured to at least one of the sections, said bracing ribs running along angularly offset corner edges of the casing.

50 4. In a manifolding assemblage having a one-use casing to be discarded when the work sheet contents are used up, including a pair of telescoping upper and lower sections to be joined against separation without destruction, both of said sections having all their walls of paper material, the combination with said sections of a metal writing plate interposed between them, 55 said plate having depending flanges some for engaging the inner surfaces of the side walls and of the intervening end wall of the lower section and some for engaging the outer surfaces of said three walls, the top wall of the upper section having a writing opening therein exposing the writing area of the writing plate, said writing opening having extended along both sides thereof strip-like portions of said top wall, said top wall portions joining the upper end of the adjacent 60 end wall of the upper section to provide corner edges for said end wall at opposite ends of the top thereof.

65 5. In a manifolding assemblage having a one-use casing to be discarded when the work sheet contents are used up, including a pair of telescoping upper and lower sections to be joined against separation without destruction, both of said sections having all their walls of paper material, the combination with said sections of a metal writing plate interposed between them, 70

75 said plate having depending flanges some for engaging the inner surfaces of the side walls and of the intervening end wall of the lower section and some for engaging the outer surfaces of said three walls, the top wall of the upper section having a writing opening therein exposing the writing area of the writing plate, said writing opening having extended along both sides thereof strip-like portions of said top wall, said top wall portions joining the upper end of the adjacent 10 end wall of the upper section to provide corner edges for said end wall at opposite ends of the top thereof, one of said depending flanges on the writing plate extending between the corner edges last-mentioned at the outer surface of the end 15 wall of the lower section.

80 6. In a manifolding assemblage having a one-use casing to be discarded when the work sheet contents are used up, including a pair of telescoping upper and lower sections to be joined 20 against separation without destruction, the top wall of the upper section having a writing opening, the combination with said sections of a metal writing plate interposed between them, said plate having depending flanges some for engaging the 25 inner surfaces of the side walls and of the intervening end wall of the lower section and some for engaging the outer surfaces of said three walls, the walls of said sections being made of paper material with the side walls being reinforced throughout their length and bracing ribs carried by said sections, said ribs applied along vertical corner edges on both sections and along side corner edges of the top wall of the upper section.

30 7. In a manifolding assemblage having a one-use casing to be discarded when the work sheet contents are used up, including a pair of telescoping upper and lower sections to be joined against separation without destruction, both of 35 said sections having all their walls of paper material, the top wall of the upper section having a writing opening, the combination of a stiffening means for said sections including a metal writing plate interposed between them, and having extensions flatwise engaging and seizing walls of the lower section; carbon sheets on the writing plate; and other extensions on said plate, there being recesses in the side walls of the lower section for receiving the extensions last-mentioned, which extensions carry means for permanently anchoring the ends of such carbon sheets in the casing.

40 8. In a manifolding assemblage having a one-use casing to be discarded when the work sheet contents are used up, including a pair of telescoping upper and lower sections to be joined against separation without destruction, both of said sections having all their walls of paper material, the top wall of the upper section having a writing opening, the combination with said sections of a metal writing plate interposed between them, said plate having depending flanges some for engaging the inner surfaces of the side walls and of the intervening end wall of the lower section and some for engaging the outer surfaces of said three walls, positioning means for the leading set of work sheets carried by the writing plate; and means for holding these work sheets on said positioning means, the means last-mentioned being carried by the upper section and connected thereto to draw the side walls of the upper section tight against certain of said flanges.

45 9. In a manifolding assemblage having a one-use casing to be discarded when the work sheet 50

- contents are used up, including a pair of telescoping upper and lower sections to be joined against separation without destruction, both of said sections having all their walls of paper material, the combination with said sections of a metal writing plate interposed between them, said plate having depending flanges some for engaging the inner surfaces of the side walls and of the intervening end wall of the lower section and some for engaging the outer surfaces of said three walls, the top wall of the upper section having a writing opening therein exposing the writing area of the writing plate, said writing opening having extended along both sides thereof strip-like portions of said top wall, positioning means for the leading set of work sheets carried by the writing plate; and means for holding these work sheets on said positioning means, the means last-mentioned carried by the upper section and connected to said strip-like portions to act as a draw-bar coupling therebetween at a point comparatively remote from that part of said top wall where uninterrupted laterally by the writing opening.
9. In a manifolding assemblage having a one-use casing to be discarded when the work sheet contents are used up, including a pair of telescoping upper and lower sections to be joined against separation without destruction, both of said sections having all their walls of paper material, the combination with said sections of a metal writing plate interposed between them, said plate having depending flanges some for engaging the inner surfaces of the side walls and of the intervening end wall of the lower section and some for engaging the outer surfaces of said three walls, said side walls being reinforced along their length, the top wall of the upper section having a writing opening, and bracing ribs applied longitudinally of the upper section, certain of said ribs being exterior of such section and some interior thereof.
10. In a manifolding assemblage having a one-use casing to be discarded when the work sheet contents are used up, including a pair of telescoping upper and lower sections to be joined against separation without destruction, both of said sections having all their walls of paper material, the combination with said sections of a metal writing plate interposed between them, said plate having depending flanges some for engaging the inner surfaces of the side walls and of the intervening end wall of the lower section and some for engaging the outer surfaces of said three walls, the top wall of the upper section having a writing opening, and bracing ribs applied longitudinally of the upper section, certain of said ribs being externally applied metal angles extending along the side corner edges of the top wall of the upper section, and others thereof being applied to the under-surface of said top wall beyond the lateral limits of the work sheets on the writing plate.
11. In a manifolding assemblage having a one-use casing to be discarded when the work sheet contents are used up, including a pair of telescoping upper and lower sections to be joined against separation without destruction, the top wall of the upper section having a writing opening, the combination of an upper section at least mainly of paper material, a lower section also at least mainly of paper material; and a metal writing plate interposed between the two sections when telescoped, said plate carrying means for positioning the same on the lower section bracingly of the latter, said lower section being folded up from a single blank of corrugated board and including side walls of two-ply thickness with the corrugations of one of said plies of each side wall extending at right angles to the corrugations of the other ply of that wall.
12. In a manifolding assemblage having a one-use casing to be discarded when the work sheet contents are used up, including a pair of telescoping upper and lower sections to be joined against separation without destruction, the top wall of the upper section having a writing opening, the combination of an upper section at least mainly of paper material, a lower section also at least mainly of paper material; and a metal writing plate interposed between the two sections when telescoped, said plate carrying means for positioning the same on the lower section bracingly of the latter, said lower section being folded up from a single blank of corrugated board and including side walls of two-ply thickness with the corrugations of one of said plies of each side wall extending at right angles to the corrugations of the other ply of that wall, said writing plate having depending flanges embracing between them inner and outer surfaces of the side walls and of the intervening end wall of the lower section.
13. In a manifolding assemblage having a one-use casing to be discarded when the work sheet contents are used up, including a pair of telescoping upper and lower sections to be joined against separation without destruction, the top wall of the upper section having a writing opening, the combination of an upper section at least mainly of paper material; a lower section also at least mainly of paper material; and a metal writing plate interposed between the two sections when telescoped, said plate carrying means for positioning the same on the lower section bracingly of the latter, said lower section being folded up from a single blank of corrugated board and including side walls of two-ply thickness with the corrugations of one of said plies of each side wall extending at right angles to the corrugations of the other ply of that wall, said writing plate having depending flanges embracing between them inner and outer surfaces of the side walls and of the intervening end wall of the lower section.
14. In a manifolding assemblage having a one-use casing to be discarded when the work sheet contents are used up, including a pair of telescoping upper and lower sections to be joined against separation without destruction, the top wall of the upper section having a writing opening, the combination of an upper section at least mainly of paper material, a lower section also at least mainly of paper material; and a metal writing plate interposed between the two sections when telescoped, said plate carrying means for positioning the same on the lower section bracingly of the latter, said lower section being folded up from a single blank of corrugated board and including side walls of two-ply thickness with the corrugations of one of said plies of each side wall extending at right angles to the corrugations of the other ply of that wall, said writing plate having depending flanges embracing between them inner and outer surfaces of the side walls.

- and of the intervening end wall of the lower section, the top wall of the upper section having an opening exposing the writing surface of the writing plate, such opening extending only at the central portion of the top wall of the upper section as far as the end wall last mentioned; a tie bar spanning such opening near said end wall; and means for holding work sheets on the writing plate included in which means is said tie bar, said tie bar being a strengthening element of the casting because connected to portions of the top wall of the upper section beyond the opposite sides of the writing opening.
15. In a manifolding assemblage having a one-use casing to be discarded when the work sheet contents are used up, including a pair of telescoping upper and lower sections to be joined against separation without destruction, the top wall of the upper section having a writing opening, the combination of an upper section at least mainly of paper material; a lower section also at least mainly of paper material; and a metal writing plate interposed between the two sections when telescoped, said plate carrying means for positioning the same on the lower section bracingly of the latter, said lower section being folded up from a single blank of corrugated board and including side walls of two-ply thickness with the corrugations of one of said plies of each side wall extending at right angles to the corrugations of the other ply of that wall, said writing plate having depending flanges embracing between them inner and outer surfaces of the side walls and of the intervening end wall of the lower section,
- 25 the top wall of the upper section having an opening exposing the writing surface of the writing plate, such opening extending only at the central portion of the top wall of the upper section as far as the end wall last-mentioned; said upper section being of chip board, and there being metal reinforcing strips of angular cross-section applied along the four vertical corner edges of both sections, and also along the two side corner edges at the top of the upper section.
- 30 16. In a manifolding device having a casing including a pair of telescoping inner and outer sections having their walls mainly of paper material, the top wall of the outer section having a writing opening, the combination with said sections of a metal writing plate interposed between them and disposed below the writing opening and having depending flanges interlocked with and bracingly engaging an end and the side walls of the inner section, the side walls of the inner section being at least of double thickness throughout a major portion of their length to adequately support the writing plate.
- 35 17. In a manifolding device having a casing including a pair of telescoping inner and outer sections having their walls mainly of paper material, the top wall of the outer section having a writing opening, the combination with said sections of a metal writing plate interposed between

them and below the writing opening and having depending flanges bracingly engaging an end and the side walls of the inner section, the outer section having bracing ribs applied along the side corner edges of the top wall thereof adjacent the writing opening whereby the top is substantially covered along the margin of the opening.

18. In a manifolding assemblage having a casing including a pair of telescoping inner and outer sections having their walls mainly of paper material, the top wall of the outer section having a writing opening, the combination of a stiffening means for said sections including a metal writing plate interposed between them and having extensions bracingly engaging the side walls of the inner section to hold the same against lateral movement, carbon sheets on the writing plate, and other extensions on the said plate carrying means for permanently anchoring the ends of such carbon sheets in the casing.

19. In a manifolding device having a pair of telescoping inner and outer sections having their walls at least mainly of paper material, the top wall of the outer section having a writing opening, and a metal writing plate interposed between the two sections when telescoped, said plate carrying means for positioning the same on the inner section bracingly of the latter, said inner section being folded up from a single blank of corrugated board and including side walls of two-ply thickness for a majority of their length with the corrugations of one of said plies of each side wall extending at right angles to the corrugations of the other ply of that wall.

20 20. In a manifolding device having a casing including inner and outer sections having their walls mainly of paper material, the top wall of the outer section having a writing opening, the combination with said sections of a metal writing plate interposed between them and disposed below the writing opening, and having means thereon engaging the side walls of the inner member to be interlocked therewith to prevent lateral movement of the side walls.

21. In a manifolding device having a casing including inner and outer sections having their walls mainly of paper material and adapted to receive for use therein continuous superposed work sheet strips, the top wall of the outer section having a writing opening, the combination with said sections of a metal writing plate interposed between them and disposed below the writing opening and over which the continuous work sheet strips are adapted to be disposed for use, and having means thereon engaging the side walls of the inner member to be interlocked therewith to prevent lateral movement of the side walls, and advanced over the platen the sections of the casing and plate being provided with aligned openings through which the fingers can be inserted and the work sheets gripped.

CARL W. BRENN.

CERTIFICATE OF CORRECTION.

Patent No. 2,178,096.

October 31, 1939.

CARL W. BRENN.

It is hereby certified that error appears in the printed specification of the above numbered patent requiring correction as follows: Page 2, first column, line 57, before the word "walls" insert end; and second column, line 60, for "flanges 27a" read flanges 27e; page 6, second column, line 58, claim 21, strike out "and advanced over the platen" and insert the same after "gripped" and before the period in line 61, same claim; and that the said Letters Patent should be read with this correction therein that the same may conform to the record of the case in the Patent Office.

Signed and sealed this 26th day of December, A. D. 1939.

Henry Van Arsdale,

(Seal)

Acting Commissioner of Patents.
